GLOVE

Karl E. Jensen, Danville, Ill., assignor, by mesne assignments, to Ervin F. Kemp, Washington, D. C.

Application November 16, 1928, Serial No. 319,779. Renewed February 18, 1933

2 Claims. (Cl. 2-161)

The invention relates generally to gloves and more particularly to reinforcing means for gloves of the type especially adapted for use in connection with the handling of rough, sharp, and heavy articles such as castings and the like.

In gloves of this general class it has been found that the greatest amount of wear occurs through the palm of the glove and the adjacent finger stalls, and also at the index finger side of the glove. It is an object of the present invention to provide a new and improved reinforcing member for strengthening the glove throughout these parts.

Another object of the invention is to provide a reinforcing means of this character which may be made of a single piece of material and is arranged to strengthen the palm of the glove, the base portion of each of the finger stalls as well as the crotches therebetween, and the side portion of the glove adjacent the index finger stall.

Other objects and advantages will become apparent in the following description and from the accompanying drawing in which:

Fig. 1 is a front view of the glove with the thumb stall turned out of the way to show a preferred form of the invention.

Figure 2 is a side view looking toward the left in Fig. 1.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In accomplishing the objects of the invention a reinforcing member or piece is provided which may be constructed as a blank and then affixed permanently to the glove. The reinforcing piece is arranged to strengthen those portions of the glove most likely to wear, namely, the palm portion of the glove, the base portions of the finger stalls, the meeting point or crotch portions of the finger stalls and the palm, and the side portion of the glove adjacent the index finger stall and the palm, all of which portions lie within a relatively small area of the front or gripping surface of the glove. In strengthening the glove, according to the present invention, the reinforcing piece is permanently secured in place overlying the palm and side edge of the glove, and includes, as integral parts of the piece, a finger

stall reinforcing flap for each finger stall, which extend outwardly from the palm toward the ends of the stalls and are secured thereto for reinforcing and protecting the stalls and crotches.

More particularly described, the preferred embodiment of the invention is shown as being applied to a commercially well-known type of glove, indicated at 5 which may include a cuff or gauntlet 6 secured thereto. A thumb stall 7 may be of the butterfly or other preferred type, and, since it forms no part of the present invention, is not described in detail.

The preferred form of the reinforcing member 10 in this instance comprises a piece of leather or other suitable flexible, wear-resisting material 70 which is previously cut in the form of a blank having a large palm covering portion 11 cut away to fit about the thumb stall 7, a side flap 12 (Fig. 2), and a series of end flaps 13, 14, 15 and 16, formed by narrowly slitting or notching the patch 75 at points corresponding to the width of the various finger stalls. The patch as shown, is firmly and permanently secured to the glove proper, preferably by means of staples 17 or wire stitching, with the side flap 12 extending around the 80 index finger side of the palm portion, and with each of the end flaps 13, 14, 15 and 16 secured to the corresponding finger stall.

The end flaps 13, 14, 15 and 16 may be of any length desired but it has been found desirable 85 to stop them short of the first finger joint in order not to impair the flexibility of the glove. The notches which separate the finger stall portions are preferably of such length that they permit free movement of each finger stall yet overlie 90 and reinforce the crotch seams, thus materially increasing the strength at these relatively weak points.

Preferably, the metallic staples or stitches are disposed, not only about the margins of the palm 95 portion, end and side flaps, but also about the entire surface of the reinforcing patch, thus forming what may be termed an interrupted metallic surface. Moreover, since these metallic pieces do not interfere with the flexibility of the glove, the 100 entire gripping surface may be provided with them to increase the wearing quality and durability of the glove.

It will be apparent from the foregoing that a reinforced glove has been provided in which the 105 reinforcing piece protects those surfaces of the glove which are most exposed to wear and in addition provides ample protection to the relatively weak crotches of the finger stalls. Moreover the reinforcing piece may be formed of a single piece 110

of material which lends itself readily to ease and low cost of manufacture.

I claim as my invention:

1. A glove having in combination with a hand covering which includes a palm and finger stalls, a reinforcing member adapted to be secured thereto, comprising a piece of flexible material shaped to provide one part for covering the palm, a second part for covering the gripping side of the index finger stall and the palm, and other flap-like parts for individually covering the portions of the finger stalls adjacent the palm and overlying the crotches therebetween, and means for securing the reinforcing member to the covering.

2. In an article of the character described, the combination of a hand protecting covering, including palm and finger portions and a reinforcing member formed in a single piece comprising a part arranged to cover the palm and to extend around the index finger side thereof and a plurality of flaps extending from the palm covering part each adapted to overlie one of the finger portions below the first finger joint, and means for securing the reinforcing member to the protecting covering throughout substantially the entire surface of the member.

KARL E. JENSEN.
